Attorney.

UNITED STATES PATENT OFFICE.

SCOTT I. PHELPS, OF CINCINNATI, OHIO.

MOLDING-POLISHER.

SPECIFICATION forming part of Letters Patent No. 337,515, dated March 9, 1886.

Application filed February 18, 1885. Serial No. 156,292. (No model.)

To all whom it may concern:

Be it known that I, SCOTT I. PHELPS, of Cincinnati, in the county of Hamilton and State of Ohio, have invented a new and useful 5 Improvement in Molding or Cornice Polishers, which improvement is fully set forth in the following specification and accompanying drawings, in which—

Figure 1 is a top or plan view of my molding or cornice polisher. Fig. 2 is an end elevation of the same, showing a piece of molding in position to be polished. Fig. 3 is a cross vertical section of the wheel for holding the sand-paper; and Figs. 4, 5, 6, and 7 are 15 sectional views of the different conformations of the guide-pieces used in the machine, against which the cornice or molding rests as it approaches the polishing-wheel.

The object of my invention is to construct 20 a machine for polishing molding for cornices; and it consists of a table having thereon at one side a vertical shaft or mandrel, which carries on its upper end a horizontal wheel which rotates on a plane directly above the top of the table. The rim of this wheel is removable in sections, so as to provide for placing therein rims of different shapes and conformations in cross-section. This rim receives the 25 sand-paper, to which it is clamped, and the whole is rotated at a high rate of speed, the molding or cornice being moved along the edge of the wheel against guides of suitable conformation, all of which will now be set forth in detail.

30 In the accompanying drawings, A represents a table mounted on a suitable frame, B. Journaled to this table, midway between the ends and at one side of the center, is a vertical shaft or mandrel, C. Near the lower end 35 is a pulley, D, by means of which it is rotated, and the upper end carries a wheel having a solid rim, E, and four or more spokes, F. On the under side of the rim E, and projecting beyond the rim E, is a flat ring, G, and directly 40 on top of the rim E is a ring, H, similar to the ring G, except that it does not project over the rim E as far as the ring G.

45 I is a removable rim, of either metal or wood, and made entire in one piece or in sections, 50 and this rim is designed to be of that conformation in cross-section which corresponds

with the kind of molding or cornice that is to be polished. Before this rim I is placed on the ring G around the rim E it is covered with sand-paper or emery-paper, and after it is placed on the ring G the ring H is placed on the rim E, and bolts J, passing down through the ring H, rim E, and also ring G, clamp the rim I and sand-paper firmly in position. In addition to the clamping-rings H G, and particularly when the rim I is made in sections, I place a disk, K, on the upper end of the shaft C. I provide the hub of the wheel with a series of holes, L, and place a pin, M, through a similar hole, M', in the rotatable disk K. 55

N represents loops designed to be placed around the rim I in a suitable groove, so that the said loops will not project beyond the face of the rim I.

O represents connecting-rods, which extend 60 from the disk K to these loops, so that when the disk K is turned and the pin M placed in the holes M' L the sections of the rim will be held firmly in place and prevented from being thrown off by the great velocity imparted to the wheel. The table at one side of the wheel is provided with removable guide-pieces. These guide-pieces P in cross-section are 65 designed to conform with the shape of the molding to be polished, and are also to be of the same conformation in cross-section as the rim I, which holds the sand-paper. Thus, Figs. 4, 5, 6, and 7 show the different kinds of guide-pieces that may be employed, and corresponding 70 with each of the conformations shown in these figures is the rim I, so that the rim I and the guides P alike may be removable and changed at will, thereby greatly increasing the efficiency of the machine by adapting it 75 for various kinds of molding. 80 85 90 95

S is a piece of molding which is in position to be polished.

Having described my invention, what I claim is—

1. A molding or cornice polisher consisting 95 of the table having thereon removable guides of the conformation of the cornice or molding to be polished, in combination with the horizontal rotatable wheel having a peripheral removable rim of like changeable conformations, 100 and provided with sand-paper for polishing purposes, substantially as herein described.

2. The horizontal rotating wheel having on the lower side of the solid rim E a projecting rim, G, and on the upper side a ring, H, with clamping-bolts J, in combination with the removable rim I, for holding the sand-paper, substantially as herein described.

3. The horizontal rotating wheel having changeable rims of different conformations, in combination with the tangential guides of like conformation in cross-section, substantially as herein described.

4. The horizontal rotating wheel having the

removable rim I, in combination with the loops N, connecting-rod O, and perforated disk K and pin M, as and for the purpose substantially as herein set forth and described.

In testimony that I claim the foregoing I have hereunto set my hand, this 7th day of February, 1885, in the presence of witnesses.

SCOTT I. PHELPS.

Witnesses:

DUGALD MCKILLOP,
J. S. ZERBE.
